SLIDE FASTENER

Arthur K. Berkner, Passaic, N. J., assignor of one-fourth to William J. Brown, Montclair, one-fourth to Peter P. Nielsen, Belleville, and one-fourth to Harry Griffinger, Newark, N. J.

Application March 17, 1942, Serial No. 435,096

1 Claim. (Cl. 24—205.5)

The invention relates to improvements in slide fasteners, and among the important objects of the invention are to provide a slide fastener arrangement which may be positively locked against movement along the complementary stringers, to provide a substantially wholly non-metallic slide which may be made of plastic or other suitable material in any desirable color and be effectively resistant to rust and discoloration, while being at the same time lighter in weight than conventional all-metal slides, and at the same time capable of construction at a lower cost.

Other important objects and advantages of the invention will be apparent from a reading of the following description taken in connection with the appended drawing, wherein for purposes of illustration a preferred embodiment of the invention is shown.

In the drawing:

Figure 1 is a fragmentary contracted front elevational view of the embodiment.

Figure 2 is a fragmentary reverse view of Figure 1.

Figure 3 is a fragmentary end elevational view showing one of the locking members of a stringer.

Figure 4 is an elevational view showing a mating pair of locking members in mated relation.

Figure 5 is a view similar to Figure 4 but showing the locking members in separated relation.

Figure 6 is an outer end elevational view of one of the locking members.

Figure 7 is a transverse vertical sectional view taken through Figure 5 along the line 7—7 and looking toward the right in the direction of the arrows.

Figure 8 is an enlarged top plan view of the slide showing the handle drawn down to releasing position.

Figure 9 is a longitudinal vertical sectional view taken substantially centrally through Figure 8.

Figure 10 is an enlarged transverse vertical sectional view taken through the body of the slide.

Figure 11 is a longitudinal sectional view taken through the removable cap.

Figure 12 is a plan view of the locking spring.

Referring in detail to the drawing, the numerals 5 and 6 generally designate the cloth or other suitable material stringers which have their inner edges confined as indicated in Figure 10 of the drawing in the slots 7 and 8 of the corresponding left and right hand locking members 9 and 10 which are cylindrical in form and are arranged in alternating staggered relation as indicated in Figures 1 and 2 of the drawing along the stringers 5 and 6. The locking

members comprise reduced segmental-shaped heads 9' and 10' which are defined by a rectangular notch 11 at one side and a substantially semi-circular cut away portion 12 on the opposite side, whereby a substantially J-shaped cross section arm 13 is defined which joins the heads with the adjacent end of the cylindrical bodies of the locking members. As indicated in Figure 5, the cut away portions 11 and 12 have their sides beveled to conformably receive the substantially beveled ends of the heads 9' and 10' due to the substantially elliptical shape of the heads when seen in horizontal section or in top plan as indicated in Figure 5 of the drawing. In adjacent locking members projecting from the opposed stringers 5 and 6, the side of the head 9' adjacent the next upper locking member is received in the right angular notch 11, while the rectangular notch 11 of the next lower locking member receives the same end of the head on the next lower locking member as indicated in the drawing, whereby lateral motion of the locking members relative to each other as well as longitudinal relative movement thereof is positively prevented, while a certain amount of flexibility is provided due to the formation of the parts.

The slide or slider which is generally designated 14 comprises the plastic material box body 15 which is open as indicated by the numeral 16 at its lower end and partly closed at its upper end as indicated by the numeral 17 by a three-quarter circular wall. The side walls are longitudinally slotted as indicated by the numerals 18 and 19, respectively, to slidably and freely accommodate the stringers 5 and 6, as clearly shown in Figure 10 of the drawing, the said side walls of the box body 15 running along the outer ends of the locking elements, and the top and bottom walls of the said body running along the upper and lower sides of the locking elements. As indicated in Figure 9 of the drawing the said side walls are discontinuous at the points indicated by the numeral 20 in substantially spaced relation to the segmental end wall 17. The box body 15 may be made of any suitable non-metallic material and may be given any desired color or ornamentation, and because of its non-metallic character, it will successfully resist rust and other objectionable features of metallic sliders, while having a substantially reduced weight, and be capable of being produced at a much lower cost. In addition, the structure and arrangement of parts described allows the slider body to be of a smaller than usual size and bulk.

The top wall 21 of the box body 15 has a longitudinal narrow depressed wall portion 22 which defines at the upper end of the top wall a right angular shoulder 23. At the lower end of the body and in alignment with the depressed por-

tion 22 is a raised lug 24. An opening 25 is provided between the lower end of the depressed wall portion 22 and the lug 24 as shown in Figure 9 of the drawing to permit the locking pin or point 26a of the locking arrangement to project to a position in between any two adjacent locking members so as to prevent the slide or slider from moving along the stringers until the point 26a has been raised out of such engagement.

The said locking point 26a is formed on one side of the lower end of a flat rectangular plate 27 which has a raised L-shaped extension or flange 28 at its upper end which fits over the shoulder 23 and is held in place by a rivet or other suitable fastener 29. In the event that the plate 27 is of spring material or of thin spring metal, the operating spring 29a may be made integral with the plate 27 by punching it out of the plate to an upwardly and longitudinally bowed shape as indicated in Figures 9 and 10 of the drawing, with the down turned terminal 30 resting on the lower end of the plate 27 over the locking point 26a and secured to the plate 27. To hold the locking spring 29 and consequently the point 26a in operative relation to the balance of the structure, a structural pin 31 is passed upwardly and longitudinally in the lug 24 to pass through a vertically elongated slot 32 in the downturned terminal 30. The elongation of the slot 32 allows the spring 29 and the plate 27 and consequently the locking point 26a a certain amount of movement relative to the body 15, sufficient to allow withdrawal of the point 26a from a position between two adjacent ones of the locking members, when the spring 29 is pulled outwardly and by grasping the finger piece 34 which has attached to it an elongated loop 35 which is trained through the bowed spring 29 as clearly shown in the drawing. Both the finger piece 34 and the loop 35 may be made of plastic or other non-metallic material or they may be made of metal. As indicated in Figure 9 of the drawing a longitudinal ridge on the top wall 36 of the body 15 projects through a portion of the slot defined in the plate 27 due to the cutting out therefrom of the spring 29a.

A cover which is generally designated 37 and which is removable upon removal of the structural pin 31 comprises a flat pan-shaped non-metallic material casing of a shape and size to fit over the top wall of the box body 15, with raised portions 38 and 39 on opposite sides of the spring 29a as indicated in Figure 10 of the drawing. The upper end wall of the cover has a tongue 40 apertured to snap over and receive the lug 41 on the upper end of the body 15, while the lower flange is apertured to pass the structural pin 31.

It will appear from the foregoing that in order to slide the slider in an upward direction so as to close the stringers 5 and 6 together and operatively connect the locking members, the finger piece 34 is pulled in an upward direction, so that the loop 35 slides along the spring 29a to the upper end thereof, thereby temporarily withdrawing the locking pin 26a from locking engagement with the locking members and permitting the slide to move along in an upward direction to effect the closure of the stringers. Upon the slider's reaching the desired elevated position along the stringers, relaxation of pull on the finger piece 34 will allow the locking pin 26a re-

turn to locking relation with the locking members. When the slider is to be operated to separate the stringers and disengage the locking members from locking relation, the finger piece 34 is pulled downwardly so that loop 35 travels to the lower end of the spring 29a and thereat the downward and outward pull thereby exerted withdraws the locking pin 26a from engagement with the locking members and permits the slider to move downwardly along the locking members and allows the locking members to separate as they emerge from the openings on the opposite sides of the segmental block or wall 17' adjacent the upper end of the box-like body, and emerge from the sides of the body through the openings defined between the discontinuities 20 of the side walls of the box body and the sides of the segmental block 17' which forms a part of the upper wall 17. From the foregoing it will be apparent that until the locking pin 26a is withdrawn by positive operation of the spring 29a, the slider will not move from the position to which it has been adjusted.

Although I have shown and described herein a preferred embodiment of the invention, it is to be definitely understood that it is not desired to limit the application of the invention thereto except as may be required by the scope of the subjoined claim.

Having described the invention, what is claimed as new is:

A slide fastener comprising a pair of separable stringers, locking elements projecting from the facing edges of the stringers alternately from said edges and comprising bodies attached to the edges of the stringers and heads on the inner ends of the bodies defined by notches on opposite sides of the bodies affording recesses for reception of portions of the heads of adjacent locking elements, a slider comprising a box having abbreviated longitudinal side walls to engage the outer ends of the bodies of the locking elements to combine said locking elements in engaged position, said side walls being longitudinally slotted to pass said stringers, said box having a segmental separator at its upper end in spaced relation to said side walls to define openings through which the locking elements pass into and out of the box, a locking spring mounted on the top wall of said box and having a locking pin normally projecting through an opening formed in said top wall to a position between two adjacent locking elements whereby movement of the slider along the stringers is positively prevented, operating means for withdrawing said locking pin to permit the slider to be moved in either direction comprising a finger piece flexibly connected to a portion of said locking spring and arranged to withdraw said locking pin from locking position and move the slider along the stringer when the finger piece is pulled in an outward and longitudinal direction, said portion of the locking spring comprising an outwardly and longitudinally bowed member with a loop slideable therealong to flexibly connect the finger piece therewith, a cover comprising a pan-shaped casing fitting on the top or outer side of said box and being apertured to expose said bowed member of the spring, and securing means removably mounting the cover on the box.

ARTHUR K. BERKNER.
